(57) **CLAIM**

The ornamental design for a communications headset, as shown and described.

DESCRIPTION

FIG. 1 is a top-left perspective view of a communications headset showing my new design;

FIG. 2 is a top-right perspective view thereof;

FIG. 3 is a top view thereof;

FIG. 4 is a bottom view thereof;

FIG. 5 is a back view thereof;

FIG. 6 is a front view thereof;

FIG. 7 is a right side view thereof; and,

FIG. 8 is a left side view thereof.

The broken lines in the drawings, including those immediately adjacent to the shaded areas, represent unclaimed features of an exemplary headset in which the design is embodied; the broken lines form no part of the claimed design.
